UNITED STATES PATENT OFFICE.

EDWARD K. LANE, OF VENTURA, CALIFORNIA.

WELL-DRILLING TOOL.

Application filed September 19, 1922. Serial No. 589,315.

To all whom it may concern:

Be it known that I, EDWARD K. LANE, a citizen of the United States, residing at Ventura, in the county of Ventura and State of California, have invented a new and useful Improvement in Well-Drilling Tools, of which the following is a specification.

My invention relates to rotary well drilling equipment and relates particularly to tools which are attached to the end of a string of drill pipe and are thereby rotated so that the cutting edges thereof will operate upon the subterranean structure being penetrated.

15 In the rotary system of drilling wells, it is often necessary to employ underreamers to enlarge the newly drilled portions of the hole below the lower end of the casing, so that the casing may be lowered into these newly drilled parts. In order to employ one of these standard underreamers, it is necessary to raise the drill bit from the well and to place the underreamer upon the lower end of the drill pipe in place thereof. The time consumed in lowering and raising a drill pipe is often as great as the time spent in actual drilling, this time spent in raising and lowering the tool from the well, of course, being dependent entirely upon the 25 depth of the hole. When an underreamer must be used, it is necessary to lower and raise the drill pipe twice for each period of drilling, thus considerably slowing down the progress. The fish tail bits used in rotary drilling are provided with a pair of diametrically disposed cutting edges and due to this characteristic formation, the tool has the tendency to jump around in the hole when in operation, and especially when 30 drilling through unevenly formed strata. In order to sharpen the fish tail bit, it is necessary to remove the tool from the end of the string of drill pipe and forge the blade back to proper shape.

45 It is an object of my invention to provide a tool having an uneven number of cutting blades so that the cutting action thereof is stabilized, and having also incorporated therewith reamer blades which operate upon the side walls of the hole and thus maintain a full diameter bore into which the casing may be lowered without the necessity of raising the string of drill pipe, placing an underreamer thereon, and again lowering into the well, for the purpose of trimming up the side walls of the bore so that the cas-

ing will advance therein, as is necessary in the integral underreamers now employed.

It is also an object of the invention to provide a reamer construction, adapted to be employed in combination with a drilling tool, having resiliently extendable reaming blades which are forced outward into contact with the side walls of the hole when the device is lowered below the bottom of the casing, and which recede into the body of the tool when it is lifted, thus allowing the tool to be lifted up through the casing when it is desired to renew the cutting and reaming blades of the tool.

70 The specific advantages of my invention and further objects thereof will be made evident hereinafter.

Referring to the drawings which are for illustrative purposes only:

75 Fig. 1 is an elevational view showing a combined drilling and reaming tool, embodying the features of my invention, in the process of drilling and reaming.

Fig. 2 is a view similar to Fig. 1, but showing the tool vertically sectioned so as to disclose the interior arrangement of parts, the lower section of the body being sectioned upon a plane represented by the line 2—2 of Fig. 5.

80 Fig. 3 is a fragmentary section similar to Fig. 2, in which the cutting blades are shown in the position they assume when being raised through a casing or into which they are depressed before lowering within the casing.

85 Fig. 4 is a bottom plan view of the lower section of the body before placement of the cutting blades.

Fig. 5 is a bottom plan view similar to Fig. 4, showing the cutting blades in place.

90 Fig. 6 is a section taken upon a plane represented by the line 6—6 of Fig. 2.

Fig. 7 is a section through the upper body member, taken as indicated by the line 7—7 of Fig. 2.

100 Fig. 8 is a view of the cutting blade.

In the form of my invention shown, I provide a body 11 which is comprised of upper and lower members 12 and 13. The upper member is provided with a tool joint pin 15 by which the tool may be attached to the lower end of a string of drill pipe 16. A trio of cutting blades 18 is mounted in the lower end of the member 13, and a similar number of expandible underreaming blades 19 are supported in the upper body member 12. The blades 19 fit into vertical slots 20 which

extend radially from the outer face of the tool inward to a central bore 22. The plates 19 are shorter than the slots 20 so that a vertical movement of the blades within the 5 slots may be attained. Near the rearward edge 25 of each blade projecting pins 26 extend outwardly into inclined grooves 27 formed in the side walls of the slots 20. In Fig. 2 the reaming blades 19 are shown in 10 their uppermost position within the slots 20. In this position of the blades, the projections 26 rest in the outer and upper ends 30 of the grooves 27, and the blades are in extended position. By moving the blades 15 19 downwardly in the slots 20, the projections 26 are caused to travel inwardly in the slots 27, thus retracting the blades into the position in which they are shown in Fig. 3.

I provide a means for normally holding 20 the blades 19 in raised position as shown in Fig. 2, this means consisting of a sleeve 31 having a radial, cupped, enlargement 32 on the lower end thereof which rests in the enlarged bore 33 at the lower end of the member 12, and is forced against the lower edges 34 of the blades 19 by a heavy spring 35. The spring 35 holds the member 31 resiliently in raised position, and due to the fact 25 that the cupped enlargement thereof is in contact with the lower edges 34 of the blades, the blades are also resiliently maintained in raised position, in which raised position they 30 are also extended. When it is desired to lower the tube into the well, the blades are 35 compressed into the slots 20. The inward movement of the blade is accompanied by a downward movement thereof owing to the engagement of the projections 26 with the grooves 27, thus the blades 19, when depressed, assume positions at the bottom of 40 their respective slots, and the member 31 is forced downwardly as indicated in Fig. 3, compressing a spring 35.

An axial hole 38 is provided in the member 12 having connection through a tubular member 39 with an axial hole 40 in the member 13, for the purpose of delivering mud to the cutting elements of the tool when the device is in operation. In order to prevent the 45 entrance of mud into the bore 22 and the bore 33 which would act to bind the member 31 so that there would be a possibility of its sticking, I thread the inner end 42 of the tubular member 31 into the body 12 at the bottom of the bore 22, so that mud entering 50 through the hole 38 will be directed by the tubular member 39 into the passage 40 in the lower body member 13. The sleeve 31 surrounds the member 39 and may slide freely 55 up or down thereupon. The blades 19 are placed in the slots 20 through the bore 33, the projections 26 entering the grooves 27 through the bore 22.

It is the purpose of the sleeve 31 to close 60 the bore 22 against the entrance of mud.

from the exterior of the tool. Upon the lower end of the tubular member 39 a plate 45 is formed which receives the thrust of the lower end of the spring 35 when the parts are assembled. This form of construction 65 makes it possible to place the spring 35 in the bore 33 and compress it by screwing in the tubular member 39 so that the assembly of the reamer element of the tool is complete whether the lower body member 13 is screwed 70 thereinto or not. When the member 13 is screwed into the member 12, as shown at 50 in Fig. 2, a conical projection 51 formed upon the lower end of the tubular member 39 extends into a counterbore 52 which is 75 shaped to form a tight joint between the tubular member 39 and the member 13, so that no leakage of mud into the bore 33 may occur around the end 51 of the tubular member. 80

I have found that where an even number of cutting blades is employed, the tendency towards chattering is more pronounced than when an uneven number of blades is provided. The employment of three cutting 85 blades 18 provides a distinct advantage over the customary two bladed rotary tool owing to the fact that where a hard spot or projection is encountered by one blade, the two opposite blades serve to oppose radial motion of the tool, so that the encountering blade cannot pass around the obstruction as happens with the use of two bladed drilling tools. When drilling with a fish tail bit, a projection at one side of the hole will 90 cause the formation of an offset pocket at the other side with the result that the blades consecutively jog back and forth between the projection and the pocket without accomplishing much reduction of the obstruction. The blades 18 provided, being radial 95 in direction, are pitched slightly forward, or in other words, the inner faces 60 thereof are tangential to the circumference of the retaining pin 61 employed for holding 100 the blades 18 in place in the member 13.

In the formation of the lower end of the member 13 a central hole 65 is drilled which is counterbored at its outer end as indicated at 66. Radially and tangentially with respect to the hole 65, slots 67 are cut in the member 13 as best shown in Fig. 4. The blades 18 are constructed of flat steel which is properly hardened after being formed 110 into the shape shown in Fig. 8. The inner edge 68 of each blade 18 is notched as indicated at 69 to receive the outstanding portions of the head 70 of the pin 61, thus providing means for preventing the removal of the blades from the slots unless the securing pin is first released by withdrawing locking pins 73 which engage a semi-circular groove 74 cut near the upper end of the pin 61. 115

In placing the blades 18 in their respec- 120

125

tive slots the blades are arranged around the head 70 of the pin 61 and the entire arrangement slipped into place, the blades entering the slots and the pin extending up into the bore 65, the head 70 thereof being received in the counterbore 66. The locking pin 73, then passed through holes provided in the body 13, engage the channel 74 and prevent the pin and the blades being removed or from coming loose while in the well.

One of the difficulties encountered in the attempted construction of replaceable blade drilling tools is the lack of strength both in the blades and the holder, with the result that the blades are apt to be broken off within the well. The construction I have developed provides a very wide blade structure as well as considerable strength 20 in the blade holder. Furthermore, the blades may be very quickly removed and replaced. If required, a stock of cutting blades 18 and underreaming blades 19 may be provided and the blades of the tool renewed each time it is raised to the surface.

When the tool is drawn from the well, the reamer blades 19 are engaged by the lower end 80 of the casing and are thus moved relatively downward in the slots as the tool is lifted within the casing. The downward movement of the blades in the slot is accompanied by an inward movement of the blades 19, due to the engagement of the projections 26 with the grooves 27, which converge as they advance downwardly; thus the blades 19 are retracted due to their engagement with the lower end 80 of the casing, and pass into the casing in closed arrangement, such as shown in Fig. 3, and offer no resistance against the lifting of the tool to the surface.

I claim as my invention:

1. In a well drilling and reaming tool, the combination of: a body adapted to be attached to a rotatable member; reaming blades having vertically disposed cutting edges radially and axially movably supported by said body; means in said body for extending said blades when they are moved in one axial direction and for retracting said blades when they are moved in the opposite axial direction; and means for resiliently forcing said blades in the axial direction in which said blades are extended, said forcing means being disposed around an axially extending tubular member which has the function of conveying liquid through said body.

2. A device, as in claim 1, in which said blades are supported in slots in said body which extend radially from the surface of said body, inwardly to an axial bore in said body; and in which device said forcing means consists of a sleeve, axially movable in said bore, having a radial enlargement at one end thereof extending over the ends of said blades, and a spring acting to force said radial enlargement against the ends of said blades.

3. A device as in claim 1 in which said blades are supported in slots in said body which extend radially, from the surface of said body, inwardly to an axial bore in said body; and in which device said forcing means consists of a sleeve axially movable in said bore having a radial enlargement at one end thereof and extending over the ends of said blades, and a spring acting to force the said radial enlargement against the ends of said blades, said sleeve being slidable upon said tubular member.

4. A device as in claim 1 in which said blades are supported in slots in said body which extend radially, from the surface of said body, inwardly to an axial bore in said body; and in which device said forcing means consists of a sleeve axially movable in said bore having a radial enlargement at one end thereof and extending over the ends of said blades, and a spring acting to force the said radial enlargement against the ends of said blades, said sleeve being slidable upon said tubular member, and in which said tubular member is threaded into said body and has a disc formed upon the outer end thereof and adapted to compress said spring against said radial enlargement on said sleeve.

5. A device, as in claim 1, having separately formed and radially disposed cutting blades for operating upon the bottom of the hole being drilled, and a tubular member to conduct lubricating liquid, past said reaming blades, toward said cutting blades.

6. A device, as in claim 1, which includes a blade holder which is threaded into the lower end of said body and has cutting blades in its lower end for operating upon the bottom of the hole being drilled, said blade holder having a passage for directing lubricating liquid from said tubular member to said cutting blades.

In testimony whereof, I have hereunto set my hand at Ventura, California, this 12 day of Sept. 1922.

EDWARD K. LANE.
